Inventor,

William Busch

UNITED STATES PATENT OFFICE.

WILLIAM BUSCH, OF ST. LOUIS, MISSOURI.

MOP OR BRUSH HOLDER.

SPECIFICATION forming part of Letters Patent No. 300,692, dated June 17, 1884.

Application filed December 26, 1883. (Model.)

To all whom it may concern.

Be it known that I, WILLIAM BUSCH, of the city of St. Louis, and State of Missouri, have invented certain new and useful Improvements 5 in Mop or Brush Holders, of which the following is a specification.

The following description is as clear and exact as I am able to give, reference being had to the drawing hereto annexed, which is a perspective view of the device.

My present invention relates to combined cleaners and attachments employed to fasten brushes, mops, and like articles to holders, rods, and staffs.

15 The implement herein described may be made of any suitable size and of any kind of metal or other suitable material. It consists of the cylindrical tube or socket, (marked A in the accompanying drawing,) into which a 20 holder, rod, or staff is inserted. This socket has a small hole in one of its longitudinal sides, with a set-screw to fasten it to or detach it from the holder or rod; or a simple nail or other device may be employed for the purpose. At the ends of the said socket are attached, and form part thereof, the flat bars or plates, (marked B and C in the accompanying 25 drawing.) Between said plates and said socket is the space marked D in the accompanying drawing. In the bar or plate B are two holes, 30 into which are inserted screws to attach to it

either a brush, duster, mop, or other like article, or into said holes may be inserted fixed pivots or simple nails, or any other device for such fastening purposes. In case of using a 35 mop, it may be attached by wire or twine to the outside of either of said plates B or C, or may be inserted through the space D, and then tied by a string or wire or any other device to this instrument. The said plate C is somewhat wider than the plate B, and the outer 40 flat and side edges of said plate C have grooved and corrugated surfaces, so that its sharp edges will when applied by any person remove, shave, and rub off any incrustation or 45 substance which is softer than the material of the implement employed.

Having thus fully described my invention, what I claim, and desire to secure by Letters Patent, is—

1. A mop or brush holder consisting of the socket A, corrugated plate C, and perforated base-plate B, substantially as described.
2. A mop or brush holder consisting of the socket A, corrugated plate C, and perforated base-plate B, in combination with a brush or other analogous article, substantially as and for the purposes set forth.

WILLIAM BUSCH.
